UNITED STATES PATENT OFFICE.

FREDERICK C. RUPPEL, OF GRAND RAPIDS, MICHIGAN.

DESIGN FOR AN AUTOMOBILE RADIATOR CAP.

Application filed May 31, 1927. Serial No. 22,224. Term of patent 3½ years.

To all whom it may concern:

Be it known that I, FREDERICK C. RUPPEL, a citizen of the United States, residing at Grand Rapids, in the county of Kent and State of Michigan, have invented a new, original, and ornamental Design for Automobile Radiator Caps, of which the following is a specification, reference being had to the accompanying drawings forming a part thereof.

Figure I is a side elevational view of the radiator cap showing my new design, and Fig. II is a front elevational view.

I claim:

The ornamental design for an automobile radiator cap as shown.

In testimony whereof I affix my signature.

FRED'K C. RUPPEL.
